UNITED STATES PATENT OFFICE

DEAN W. DAVIS AND THOMAS M. HARDY, OF PENDLETON, INDIANA, ASSIGNORS TO
NATIONAL LABORATORIES CORPORATION, OF PENDLETON, INDIANA, A CORPORA-
TION OF INDIANA

OZONE-PRODUCING DEVICE

Application filed June 26, 1929. Serial No. 373,808.

This invention relates to the art of producing ozone and particularly to portable units adapted to be operated in private homes, offices, dining cars and the like where 5 purification and deodorizing of the air is desired. The principal objects of the invention reside in the provision of a compact unit designed to use the minimum of current in proportion to the ozone produced; that may be 10 absolutely safe in the hands of all users regardless of the location of the unit and that may be subject to long life and not affected by the mechanical action of the ozone.

Other objects reside in the formation of 15 the condenser and also in the means of locating and holding it in position in the unit to permit a current of air to pass readily therethrough and to permit easy and quick assembly of the various parts.

20 These and other objects will become apparent in the following description of the one particular form of the invention as now best known to me as illustrated in the accompanying drawing, in which—

25 Fig. 1 is a fragmentary top plan view of a unit embodying our invention;

Fig. 2, is a fragmentary side elevation;

Fig. 3, a horizontal transverse section on the line 3—3 in Fig. 2;

30 Fig. 4, a vertical section through the condenser on the line 4—4 in Fig. 3;

Fig. 5, a wiring diagram; and

Fig. 6, a bottom plan view of the unit.

Like characters of reference indicate like 35 parts throughout the several views in the drawings.

We form a transformer core 10 of the laminated type here shown as rectangular in shape, on one side of which we place a primary winding 11 and on the opposite side the secondary winding 12. The core 10 is spaced substantially centrally between an upper plate 13 and a lower plate 14 by the studs 15, one at each corner. Within the space bounded 40 by the sides of the core 10, we position a condenser of the following description.

We first form one side of the condenser by taking a number of U-shaped members 16, 17, and 18 each with spaced apart vertically positioned parallel plates and nest the three

members together as indicated in Fig. 3 to have the webs interconnecting the respective plates of each of the members compressively held together by a bolt or rivet 19 passed centrally therethrough to finally secure the 55 three pieces so arranged against an insulating board 20 which has the legs 21 and 22 bent around normal to the board and spaced outwardly from the plates of the member 18. The other side of the condenser is formed 60 in exactly the same manner by employing the three U-shaped members 23, 24 and 25 to have the webs between the plates compressively held together by the rivet 26 also securing the assembled three members compressively against the insulating board 27 which has the legs 28 and 29 bent around into the same planes as those of the legs 21 and 22. 65

The last named assembly of the members 23, 24 and 25 is positioned on the board 27 70 so that when the two sides of the condenser are assembled the plates of those members will extend between and lie equidistant from the plates of the members 16, 17, and 18.

All of the plates of the various members 75 are provided with a plurality of studs 30 projecting from each of their vertical faces. A sheet of insulating material 31, preferably mica, is bent to lie along one of the vertical faces of each of the plates of the members 80 16, 17 and 18 and to pass around the extreme outer end and thence backwardly along the other vertical face. By placing one of these insulators 31 about each of the plates of those members, an insulated partition is thereby 85 positioned between each of the plates of the members 16, 17 and 18 and the next adjacent plates 23, 24 and 25. The height of the studs 30 and the thickness of these insulators 31 are such that when completely assembled the 90 insulators will be contacted by the studs of the plates and the plates will be held thereby parallel one to the other.

Rectangular holes are formed in the metal plates 13 and 14 to receive therethrough the 95 insulating boards 20 and 27, the height of both of these boards being such that they will extend substantially through the plates 13 and 14 to have their outer ends practically flush with the outer faces of the respective 100

plates. Now to secure the two boards 20 and 27, we place the side insulating boards 32 and 33 down between the boards 20 and 27 against the inner faces of the respective legs of the two boards, as indicated in Fig. 3, the lengths of the boards 32 and 33 being sufficient to compressively engage the boards 20 and 27 against the sides of the holes through the plates 13 and 14. The width of the holes through the plates 13 and 14 are such that when the boards 32 and 33 are placed into position as above indicated, the legs 21 and 28 will be pressed outwardly against the one side of the hole and the legs 22 and 29 against the opposite side, and will compress all of the insulators 31 on the plates therebetween one against the other so that the insulating members are frictionally held in vertical position against the studs of the plates with intervening air spaces past the studs between the plates and the insulators 31.

It is to be noted that the plates from the respective sides of the condenser terminate at some distance back of the webs of the opposite members.

The condenser as above described substantially fills the area between the windings 11 and 12 and the sides of the core 10. The boards 20 and 27, in fact, bear against the inner sides of the core. The assembly of the transformer with the condenser therein is positioned within a housing 34 as indicated in Figs. 1 and 2 to have the plates 13 and 14 fitting against the vertical walls therearound and the entire space between these plates is preferably filled with an insulating compound 35 which may be poured in to effectively seal the two windings and the core 10 against any oxidizing action from without. The plate 13 is spaced below the top of the housing 34 and the plate 14 is at a distance above the bottom of the housing. The studs 15 project downwardly from the plate 14 through a lower cover plate 36 with spacers 37 therebetween and extend on below the plate 36 to carry the buttons 38 on which the housing rests. The plate 36 is provided with a plurality of perforations 39 therethrough at each end, the plate being entirely closed across the area under the condenser.

The top side of the housing 34 is depressed at each end and has a number of louvers 40, here shown as three in number in each of these depressions, so arranged that articles 55 such as wires or the like may not readily be inserted therethrough to reach the plates in the condenser.

Thus it may be seen that there may be a passage of air upwardly through the holes 39 in the plate 36 across and upwardly vertically between the plates of the condenser and thence laterally and upwardly through the louvers 40.

By placing the terminals of the winding 11 in circuit with a suitable source of pulsating

or alternating current, a current is induced in the secondary winding 12 to build up charges of opposite characters on the respective plates in the condenser to have an electrical discharge created thereby for producing the desired ozone.

To some persons, the odor produced about a source of ozone is disagreeable, and to overcome that objection, we insert a piece of absorbent material 41 on the lower plate 36 over which the air current passing from the holes 39 into the condenser may pass. A hole 42 is made in the plate 36, through which a few drops of some volatile, pleasing odorous substance, such as oil of pine, may be dropped by turning the housing 34 upside down, to be absorbed by the material 41. Now with the housing 34 returned to its normal upright position, the air current passing over the material 41 will pick up the volatilized substance and hence carry it on into the room.

We claim:

1. In an ozone producing device, a transformer core, a primary winding on the core, a secondary winding on the core, said core being closed, a group of condenser plates, a second group of condenser plates electrically separated from the first group, all of said plates being vertically disposed with openings therebetween at the top and bottom ends, the first group being electrically connected to one of the terminals of said secondary winding and the second group being electrically connected to the other terminal of said secondary winding, and an insulating wall about both of said groups defining a vertically disposed air conduit including all of said plates therewithin, studs projecting from the faces of said plates, insulating members between adjacent plates, and said insulating wall compressively forcing said plates against the intervening insulating members.

2. In an ozone producing device, a transformer core, a primary winding on the core, a secondary winding on the core, said core being closed, a group of condenser plates, a second group of condenser plates electrically separated from the first group, all of said plates being vertically disposed with openings therebetween at the top and bottom ends, the first group being electrically connected to one of the terminals of said secondary winding and to the second group being electrically connected to the other terminal of said secondary winding, and an insulating wall about both of said groups defining a vertically disposed air conduit including all of said plates therewithin, an upper plate, and a lower plate, each of said plates having a hole therethrough into which the respective top and bottom ends of said insulating wall engage.

3. In an ozone producing device, a transformer core, a primary winding on the core, a secondary winding on the core, said core being closed, a group of condenser plates, a sec-

- ond group of condenser plates electrically separated from the first group, all of said plates being vertically disposed with openings therebetween at the top and bottom ends, 5 the first group being electrically connected to one of the terminals of said secondary winding and to the second group being electrically connected to the other terminal of said secondary winding, and an insulating wall about 10 both of said groups defining a vertically disposed air conduit including all of said plates therewithin, an upper plate, and a lower plate, each of said plates having a hole therethrough into which the respective top and bottom ends 15 of said insulating wall engage, and a sealing material completely filling all of the space between said upper and lower plates, about said insulating wall and around said primary and secondary windings.
- 20 4. In an ozone producing device, a closed transformer core, a primary winding on the core, a secondary winding on the core, said core having a central opening between said two cores, an upper plate, a lower plate, 25 means holding said two plates in fixed relation with said core lying therebetween, each of said plates having a hole therethrough above and below said core opening, a wall engaged within said holes and passing 30 through said core opening to define an air conduit therethrough, and a condenser held within said wall having vertical passages therethrough, said condenser being connected across the terminals of said secondary 35 winding.
5. In an ozone producing device, in combination with an upper and a lower holding plate each having a hole therethrough, a U-shaped insulating board, a group of U-shaped 40 condenser members each having a pair of parallel vertically positioned plates spaced apart by webs of increasing length, each of said members being nested and secured one to the other with the web of one on the web of 45 the next member therearound, said group being mounted on said insulating board, a second group of U-shaped condenser members similarly formed to said first group, a second U-shaped insulating board, said second 50 group being mounted on said second board but offset thereon in relation to said first group, said first and second boards being positioned between said upper and lower plates to have their ends project into said holes and 55 to have the condenser member plates of one group straddle the condenser plates of the second group, and side insulating boards compressively engaging by their ends said first and second U-shaped insulating boards.
- 60 6. In an ozone producing device, in combination with an upper and lower holding plate each having a hole therethrough, a U-shaped insulating board, a group of U-shaped condenser members each having a pair of parallel vertically positioned plates 65 spaced apart by webs of increasing length, each of said members being nested and secured one to the other with the web of one on the web of the next member therearound, said group being mounted on said insulating board, a second group of U-shaped condenser members similarly formed to said first group, a second U-shaped insulating board, said second group being mounted on said second board but offset thereon in relation to said first group, said first and second boards being positioned between said upper and lower plates to have their ends project into said holes and to have the condenser member plates of one group straddle the condenser plates of the second group, and side insulating boards compressively engaging by their ends said first and second U-shaped insulating boards, and insulating members along and between the vertical faces of adjacent condenser plates, said side boards compressively engaging said condenser plates and said insulating members one against the other, and studs projecting laterally from said condenser plates spacing said insulating members therefrom forming thereby vertically disposed air passages between said condenser plates and the adjacent insulating members.
8. In an ozone producing device, a closed transformer core, a primary winding on the core, a secondary winding on the core, said core having a central opening between said two cores, an upper plate, a lower plate, means holding said two plates in fixed relation with said core lying therebetween, each 125

of said plates having a hole therethrough above and below said core opening, a wall engaged within said holes and passing through said core opening to define an air conduit therethrough, and a condenser held within said wall having vertical passages therethrough, said condenser being connected across the terminals of said secondary winding, and means for holding a volatile fluid immediately adjacent said air conduit.

10 In testimony whereof we affix our signatures.
